UNITED STATES PATENT OFFICE.

ALVIN FLAVEL NIMS, OF PHILADELPHIA, NEW YORK.

CONCRETE-MIXING MACHINE.

No. 851,553.

Specification of Letters Patent.

Patented April 23, 1907.

Application filed March 27, 1906. Serial No. 308,236.

To all whom it may concern:

Be it known that I, ALVIN FLAVEL NIMS, a citizen of the United States, and a resident of Philadelphia, in the county of Jefferson and State of New York, have invented a new and Improved Concrete-Mixing Machine, of which the following is a full, clear, and exact description.

The purpose of the invention is to provide a simple, durable and economic machine for mixing concrete or other material, and to so construct the machine that it may be used for mixing batches, or for receiving a continuous feed during operation.

Another purpose of the invention is to provide a machine of the character described, which will thoroughly mix material in a very short time and one in which the material may be permitted to remain in the machine for any desired length of time, or be released at intervals, or released at any time deemed proper.

A further purpose of the invention is to provide a concrete mixing machine so constructed that a view may be obtained of the interior of the machine at any time, whereby the progress of the mixing operation can be observed, and so that liquid may be simultaneously supplied to all of the compartments or to any particular compartment or group of compartments, or cut off from all.

The invention consists in the novel construction and combination of the several parts, as will be hereinafter fully set forth and pointed out in the claims.

Reference is to be had to the accompanying drawings forming a part of this specification, in which similar characters of reference indicate corresponding parts in all the figures.

Figure 1 is a side elevation of the improved machine, parts being broken away; Fig. 2 is a view of the delivery end of the machine; Fig. 3 is a plan view of the machine with the parts in the position shown in Fig. 1; Fig. 4 is a side elevation of the first, or receiving cube of the machine in a position the reverse of that shown in Fig. 1, a portion of the cube being broken away to show its interior construction; and Fig. 5 is a diagrammatic view of two cubes, one in full lines and the other in dotted lines, showing the manner in which they are brought into communication.

The body of the machine, which is adapted to revolve as will be hereinafter set forth, consists of any desired number of cubes. In the drawings two connected cubes are shown,

the receiving cube being designated as A and the delivery tube as B; and when a greater number of cubes are employed in the construction of the body the receiving cube is 60 always constructed like the cube A, and the delivery or dispensing cube like the cube B. The cubes A and B are both hollow, and the cube A at its outer end at one corner is provided with an opening 10 into which the material is introduced to be mixed, and at the opposite corner of the cube in its inner face a rectangular opening 11 is made, and the cuts for this opening extend from the edges to the central portions of the sides of the cube in 70 which the opening is produced, as is shown best in Fig. 5.

A partition or shelf C is located in the cube A, occupying a position which is one-third the distance from one opposing face of the cube, 75 thus dividing said cube into two chambers, one practically two-thirds of the depth of the cube and the other chamber one-third of such depth. This partition C is provided at about its center with an opening 12, usually 80 rectangular, and this opening 12 faces the inner end of the cube A, as is illustrated in Figs. 1 and 4. A side member 13 of the said partition engages with an inner side wall of the cube throughout the length of the said 85 wall, being that side wall through which a portion of the opening 11 extends. Another member 13^a extends in engagement with the inner face of the outer end wall of the said cube A the full length of the said end wall, 90 while a third member 13^b is in engagement with the inner face of the opposite side wall of the cube, but does not extend to the inner end wall of the cube C, thus providing a space 95 17 between the inner end of the member 13^b and the opposing wall of said cube A. The member 13 is given more or less of a downward inclination in direction of the inner end of said cube, and the outer edge of the member 13 extends parallel with the edge of the 100 opening in the side of the cube and terminates at what may be termed the bottom wall of said opening 11, as is shown best in Figs. 1 and 4. The inner edge of the member 13 is provided with a flange 14 extending up 105 into the smaller chamber of the cube.

A tongue 16, preferably inclined upon its inner edge, extends down from the inner end of the member 13^b of the partition C to an engagement with the opposing wall of the 110 cube, thus forming a continuation of the space or passage 17; but the outer longitudi-

nal edge of the tongue 16 engages with the inner face of the adjacent side wall of the cube A, as is shown by dotted lines and is indicated in Fig. 4. Thus communication is established between the two chambers of the cube through the passage 17 and the opening 12.

The delivery cube B is provided at its inner end, or the end opposed to the inner end of the cube A, with a rectangular opening 18, corresponding in position to the opening 11 in the cube A; and when these cubes are brought together they are made to practically interlock at their opposing openings 11 and 18, as is best indicated in Fig. 5, but is shown also in Fig. 1, whereby to establish communication between the cubes. Where the two cubes A and B are brought together they are connected preferably by suitable angle irons 18^a, as is shown in Figs. 1 and 3.

An opening 19 is produced in the corner of the outer end of the delivery cube B, which opening is opposite the opening 18. This opening 19 has a straight base and a straight inner face 19^a, and an outer opposing inclined wall 19^b; and an upper wall 19^c that extends unbroken from the wall 19^a to the wall 19^b. The opening 19 being a corner opening extends through only three faces of the cube, but deepest in one face as is shown in Fig. 2.

The member 13 of the partition C in the cube A may be termed a chute member, since it directs material to the connected openings 11 and 18 in the two cubes; and in the delivery cube B a corresponding chute C' is provided, similarly located to the aforesaid chute member 13 of the cube A, and this chute C' occupies the same relative position to the cube B as does the chute member 13 to the cube A, the chute C' extending from the inner end wall of the cube B at two-thirds its height to the lower wall of the opening 19 at the delivery end of the said delivery cube B; and at the inner edge of said chute C', which is also practically a partition, a flange 21 is provided, extending into the shallower chamber of the cube, since the chute C' is so placed that the space between it and one wall of the cube will represent one-third of the depth of the cube as in the arrangement of the partition C in the cube A. The flanges 14 and 21 serve to prevent the material sliding from the chutes and also tends to direct said material to the openings at the ends of the chutes.

A door 22 is provided for the rear opening 19, which door is pivoted by a suitable pin 23 to one side of the cube B, that side in which the triangular wall of the opening 19 is produced. Said door is not intended to entirely cover the opening 19 when the door is closed, as at such time a space is left between the upper edge of the door and the upper wall 19^c of said opening as indicated by

dotted lines in Fig. 2, whereby the person is enabled at all times to look into the machine and note the progress of the mixing operation, as by means of the aligning openings in the cubes almost the entire interior of the cubes is rendered visible.

The upward movement of the door 22 is limited by contact with a suitable stop 24 adjacent to its pivot point, and two stops 25 and 26 extend out from the said door, as is also shown in Fig. 2. The upper stop 25 is adapted to be engaged by a spring latch 27, secured to an end face of the said cube B for the purpose of holding the door 22 in an upper position, the lower stop 26 being adapted for engagement by the head of a similar latch 28, attached to said face of said cube B for the purpose of holding the door closed. The downward movement of the door is limited by engagement with suitable brackets 28^a. The head of the latch 27 is provided with a horizontally-extending pin 29, and the head of the latch 28 is provided with a corresponding pin 30.

In mounting the connected cubes A and B, parallel sills 31 are laid on any suitable support, and on each sill uprights 32 are secured, having suitable boxes at their upper ends to journal shafts 33, one of which shafts is provided with a gear 34 near its rear end, and each shaft is provided with two flanged wheels 35, the flanges of the wheels on the other shaft 33 being at the opposing faces of the wheels, as is best shown in Fig. 1. The shaft 33 carrying the gear 34 is provided at its rear end with a driving pulley 36, and said pulley 36 carries a belt 37 connected with any suitable source of power. The two cubes are simultaneously turned at the same rate of speed.

A ring guide 38 is secured by means of suitable spokes 38^a to the corner portions of each cube A and B, and these ring guides are adapted to engage with the guide wheels 35 on the shafts 33, and by reason of the particular location of the flanges on said guide wheels the body of the machine is prevented from moving forward or rearward. Preferably integral with the guide ring 38 on the cube A an annular ring 39 is formed, provided with exterior teeth whereby the said ring is a skeleton gear, and the teeth of this gear mesh with the teeth of the gears 34 on the shafts 33, whereby a rotary movement is imparted to the body of the machine as the shafts 33 are turned. Uprights 40 are carried up from the sills at the receiving end of the machine, and these uprights support a hopper 41 having a lower contracted lower portion 42 that extends into the opening 10 at the receiving end of the receiving cube A.

At the delivery end of the machine two standards 43 and 43^a are erected on the sills 31, the standard 43^a being of less height than the standard 43. These standards are usu-

ally provided with metal braces 44 attached to them and to the sills, and these braces extend over the top of the standards 43 and 43^a some distance beyond the inner faces of the 5 said standards.

On the upwardly-extending end of the brace for the standard 43 a trip lever 46 is pivoted; and upon the corresponding portion of the brace for the standard 43^a a second trip lever 47 is mounted to turn. If the door 22 is open and it is desired to close said door at a certain time in the revolution of the body of the machine, or whenever the door is to be closed while the machine is in operation, the lever 46 is turned until its inner end is in the path of the pin extension 29 from the upper latch 27, and therefore when this pin engages with the lever 46 the latch is lifted from the stop 25 and the door will fall 20 to closed position by gravity. When it is desired to open the door while the machine is in operation, for the purpose of discharging the contents of the body, the lever 47 is brought into position to engage with the projecting pin 30 from the lower latch 28, whereupon the latch is disconnected from the lower pin 26, and as that portion of the body having the outlet opening 19 therein is carried downward the door opens by gravity and by engagement with the upper latch 27 is held 30 open until purposely released. A spout or chute 48 is secured at the delivery end portion of the machine, usually by attachment to the uprights 43 and 43^a; and as the material flows out from the delivery opening 19 in the delivery cube B the material is received in the said spout 48.

A pipe 49 is led from any source of water supply. This pipe at its lower end, or end 40 adjacent to the machine, is provided with a bifurcated fitting 50, so that two branch pipes 51 and 52 can be connected with the main supply pipe 49, and each branch pipe 51 and 52 is provided with a controlling 45 valve 53. Both pipes 51 and 52 are led into the body of the machine through the receiving opening 10. The pipe 52, for example, terminates in the receiving cube A while the pipe 51 is carried through into the delivery 50 cube B. The inner end of the pipe 52 is supported ordinarily by a bracket 54 attached to the pipe 51, and the inner end of the pipe 51 is loosely mounted in a bearing 55, preferably secured to the under face of the chute C' in 55 the delivery cube B as is shown in Figs. 1 and 3. The pipe 52 at its inner end portion is provided with apertures 55^a for the escape of water therefrom, and the inner end of the pipe 51 located in the delivery cube B is provided with suitable apertures 56^a for a similar purpose. Thus it will be observed that water, or any desired liquid, can be supplied 60 individually to either of the cubes, or can be supplied to all of the cubes; and if a number 65 of cubes are employed to form the body por-

tion of the machine, water or liquid could be supplied to any particular group of cubes.

In the operation of the machine, as the cube sections are revolved the entering material will drop to the lowest point in the receiving cube section A, sliding from corner to corner, and will continue thus to change its position in the large chamber of said receiving cube section A, and in traveling along the under face of the partition or shelf C in 70 said receiving cube section A said material will be further mixed. In thus traveling the material passes through the opening 12 in the said partition C and through the passage 17 to the smaller compartment, where by thus 75 tumbling it is further mixed until it reaches the chute member 13 of the partition C, by which it is conducted to the registering openings 11 and 18, where it is again tumbled from corner to corner in the delivering or dispensing cube section B, until finally landing 80 upon the chute C' it passes out through the exit opening 19 in the delivery or dispensing cube section B, provided said opening is uncovered, and during the entire process, 85 whether the door 22 is open or closed the attendant will have a full view of the interior of the cube sections.

The tongue 16, extending down from the partition C in the receiving cube section A, is 90 particularly designed to deflect the material from a straight passage to the communicating openings 11 and 18, provided the material enters the receiving cube section A when in a position intermediate of its proper receiving or delivery positions, since at such time the material will strike the said tongue 16 and will be forced to undergo the same circuit or procedure as if the material were entered at the most favorable position of the 95 said cube section.

Having thus described my invention, I claim as new, and desire to secure by Letters Patent,—

1. In a concrete mixing machine, connected hollow cube sections one mounted upon the other at an end portion but both being mounted to revolve in unison and having registering openings in their opposing surfaces, the first cube section being provided with an inlet opening and the last with an outlet opening, a chute extending from the receiving end of the first cube section leading to the said registering openings, and a second chute extending from the inner end wall of the last cube section to the outlet thereof.

2. In a concrete mixing machine, connected hollow cube sections mounted to revolve, having registering openings in their opposing surfaces, the first cube section being provided with an inlet opening and the last with an outlet opening, a partition located within the first cube section, having an opening therein and having one member separated from the inner wall of the said first cube sec-

tion, which member is provided with a tongue at right angles thereto, extending to an engagement with a wall of the said first cube section, another member of the partition being inclined, leading to the said registering openings, and an inclined chute located within the last cube section, in alignment with the inclined member of the said partition in the first cube section, the chute in the last cube section extending from its inner wall to the outlet opening.

3. In a concrete mixing machine, connected hollow cube sections mounted to revolve, having registering openings in their opposing surfaces, the first cube section being provided with an inlet opening and the last with an outlet opening, a partition located within the first cube section, having an opening therein and having one member separated from the inner wall of the said first cube section, which member is provided with a tongue at right angles thereto, extending to an engagement with a wall of the said first cube section, another member of the partition being inclined, leading to the said registering openings, and an inclined chute located within the last cube section, in alignment with the inclined member of the said partition in the first cube section, the chute in the last cube section extending from its inner wall to the outlet opening, the said chute and the said partition being located above the center of their respective cube sections, and the communicating openings in the said cube sections being rectangular, and the cube sections having interlocking connection at the points where the openings occur.

4. In a concrete mixing machine, hollow cube sections located one upon the other at their end portions and having interlocking connection and registering openings at their point of connection, the receiving cube section being provided with an inlet opening and the dispensing cube section with an outlet opening, and a partition located in the receiving cube section, extending from its outer wall to the said opening connecting the two sections, the dispensing cube section being provided with a chute correspondingly located to the said partition in the receiving cube section, and leading from the inner end wall of the said dispensing cube section to the outlet opening therefor and means for revolving the connected cubes.

5. In a concrete mixing machine, hollow cube sections mounted to revolve and having interlocking connection and registering openings at their point of connection, the receiving cube section being provided with an inlet opening and the dispensing cube section with an outlet opening, a partition located in the receiving cube section, extending from its outer wall to the said openings connecting the two sections, the dispensing cube section being provided with a chute correspondingly located to the said partition in the receiving cube section and leading from the inner end wall of said dispensing section to the outlet opening therefor, means for rotating the said cube sections, a door for the outlet opening of the dispensing cube section, adapted to open and close by gravity, latches for the said door in its upper and in its closed positions, and trips for the said latches independent of the said cube sections and the said door.

6. In a concrete mixing machine, hollow cube sections mounted to revolve, having interlocking connection and registering openings at their point of connection, the receiving cube section being provided with an inlet opening and the dispensing cube section with an outlet opening, a partition located in the receiving cube section, extending from its outer wall to the said openings connecting the two sections, the dispensing cube section being provided with a chute correspondingly located to the said partition in the receiving cube section and leading from the inner end wall of said dispensing section to the outlet opening therefor, means for rotating the said cube sections, a door for the outlet opening of the said dispensing section, adapted to open and close by gravity, latches for the said door in its upper and in its closed positions, trips for the said latches, independent of the said cube sections and the said door, said door being of less depth than the depth of the outlet opening, and means for independently and collectively supplying liquid to the interior of the said cube sections.

In testimony whereof I have signed my name to this specification in the presence of two subscribing witnesses.
